UNITED STATES PATENT OFFICE.

HARRY SLADE, OF WAKEFIELD, ENGLAND, ASSIGNOR OF ONE-HALF TO FRANCIS WILLIAM GREEN, OF WAKEFIELD, ENGLAND.

CONSTRUCTION OF TUBE JOINTS FOR FUEL ECONOMIZERS FOR STEAM BOILERS AND THE LIKE.

Application filed July 16, 1921. Serial No. 485,241.

(GRANTED UNDER THE PROVISIONS OF THE ACT OF MARCH 3, 1921, 41 STAT. L., 1313.)

To all whom it may concern:

Be it known that HARRY SLADE, a subject of the King of Great Britain, residing at Wakefield, Yorkshire, England, has invented certain new and useful Improvements in the Construction of Tube Joints for Fuel Economizers for Steam Boilers and the like (for which I have filed application in Great Britain April 20, 1916, Patent No. 104,078), of which the following is a specification.

The object of this invention is to construct the joint between a header and tube so that perfect safety is obtained for high pressures and that no machined part of the tube comes in contact with the gases.

My invention will be clearly understood from the following description aided by the annexed drawings in which Figure 1 is a section of top and bottom headers of a fuel economizer with a tube (broken) connected with same.

Figure 2 is a section on the line *a a* of Figure 3.

Figure 3 is a section on the line *b b* of Figure 1.

For the purpose of my invention the ends 1, 2 of the tube 3 are tapered, the inner ends of the tapers having a shoulder 4, 5 as usual.

The top and bottom headers 6, 7 are provided with lugs, bosses or the like 8 having screw threaded holes 9 and preferably four for each tube 3.

I construct a ring plate 10 having holes to correspond to the holes 9 in the lugs or bosses 8 and preferably of a shape corresponding externally to the shape of the header 6 or 7 surrounding the tube 3 and the inside of this ring plate 10 is of a diameter exactly equal to or slightly larger than the largest external diameter of the tube so that such ring plate 10 can be passed along the tube 3 from either or one end, and in one surface from one edge of the ring plate 10 I form a groove or recess 11 the recess or groove 11 being on the side next to the header 6 or 7.

Between the ring plate 10 and the header 6 or 7 and in the groove 11 I position a split

metal ring 12 which has a bearing on the header 6 or 7 and also on the shoulder 4 or 5 of the tapered portion 1 or 2 of the end of the tube 3 and on bolting the ring plate 10 to the header by a bolt 13 the split metal ring 12 is held in position and firmly holds the tube 3 in place the machined parts of the tube being protected from the effect of the gases.

What I do claim as my invention and desire to secure by Letters Patent is:—

1. A fuel economizer comprising in combination, a tube, a hollow member at one end of said tube whereby the latter may be connected to an adjacent tube, a hollow member at the opposite end of said tube whereby the latter may be connected to an adjacent tube, the exteriors of the opposite ends of said tube being tapered, each of said hollow members being provided with a conical seat adapted to receive a tapering end of said tube, a pair of shoulders each provided at the larger end of the taper at each end of said tube, a pair of split rings each adapted to engage a corresponding one of said shoulders and to overlie and seal a corresponding one of the joints between the tapered ends of said tube and said members, clamping elements each adapted to engage a corresponding one of said rings to force the latter into joint-sealing position, and means for applying pressure to said clamping elements and for holding them in clamping position.

2. In a device of the class described, in combination, a tube, a hollow member at one end of said tube whereby the latter may be connected to an adjacent tube, a hollow member at the opposite end of said tube whereby the latter may be connected to an adjacent tube, the exteriors of the opposite ends of said tube being tapered, each of said hollow members being provided with a conical seat adapted to receive a tapering end of said tube, a pair of shoulders each provided at the larger end of the taper at each end of said tube, a pair of split rings each adapted to engage a corresponding one of said shoulders and to overlie a corresponding one of the joints between the tapered

ends of said tube and said members, clamping elements each adapted to engage a corresponding one of said rings to force the latter into joint-engaging position, and means for applying pressure to said clamping elements and for holding them in clamping position.

In testimony whereof I have hereunto set my hand in presence of two subscribing witnesses.

HARRY SLADE.

Witnesses:

JAMES HEPTOMHALL,
WILLIAM HENRY MORRIS.
